Inventor

Wm Timmins,

UNITED STATES PATENT OFFICE.

WILLIAM TIMMINS, OF WILSONVILLE, NEBRASKA.

HAME-TUG.

SPECIFICATION forming part of Letters Patent No. 519,030, dated May 1, 1894.

Application filed October 27, 1893. Serial No. 489,305. (No model.)

To all whom it may concern:

Be it known that I, WILLIAM TIMMINS, a citizen of the United States, residing at Wilsonville, in the county of Furnas and State of Nebraska, have invented a new and useful 5 Hame-Tug, of which the following is a specification.

My invention relates to improvements in hame-tugs; and the objects in view are to provide a cheap, simple, and durable construction of hame-tug, the same being so constructed as to be flexible so as to conform to the contour of the sides of the horse, and readily adjustable as to lengthen and shorten the tug in 15 conformity with the length of the horse.

With these and other objects in view the invention consists in certain features of construction hereinafter specified and particularly pointed out in the claims.

Referring to the drawings:—Figure 1 is a 20 perspective view of a hame-tug embodying my invention. Fig. 2 is a longitudinal sectional view. Fig. 3 is a detail in perspective of the tug, the tug-strap and trace removed.

Like numerals of reference indicate like 25 parts in all the figures of the drawings.

In practicing my invention I employ a tug-plate 1 of oblong shape, the same having its opposite edges bent to form flanges 2 outwardly disposed and parallel to each other, the said flanges being connected near their 30 front and rear ends by keepers 3. The bottom of the plate is provided with a series of transverse slots 4, whose edges are rounded

35 or flared so as to permit of a ready entrance. A trace-plate 5 is located at the rear end of the tug-plate 1, has its rear end transversely slotted, as at 6, and connected to the trace 7, and at its front end is reduced forming a 40 tongue 8, which is passed through the rear transverse slot 4 of the tug-plate from the rear side thereof and bent over forming a loose connection. The plate 5 is further provided upon its upper side with a keeper 9.

45 Located within the tug-plate 1 and fitting loosely between the flanges 2 thereof is an adjusting plate 10, which at its front end is reduced to form a tongue 11, and at its rear end is inwardly bent to form a tongue or hook 12.

50 This tongue 12 is thickened at its wearing portion and removably engages with any one of the aforesaid transverse slots 4 with which

the tug-plate is provided. The adjusting-plate 10 near its front end is provided upon its outer side with a keeper 13. The tongue 11 55 is passed through a slot 14 formed in the rear end of a buckle-plate 15 and bent over the rear end thereof, whereby a flexible or loose connection is formed between the adjusting-plate 10 and the buckle-plate 15. It will be 60 understood that these plates 1, 5 and 15 are preferably formed of malleable metal so that they may be readily connected and their tongues bent to form the loose connection.

The front end of the buckle-plate 15 is engaged with the rear transverse bar of an ordinary buckle 16 of any desired construction, or it may be engaged with the pintle-bar of a buckle for which purpose the aforesaid buckle-plate is provided adjacent to its front end 70 with a slot or opening 17. The front end of this buckle-plate is bent around the bar so as to loosely engage the same.

The tug-strap 18 terminates at its front end in the eye 19 which is of the usual construction and is designed to engage with the hames. The said eye being in engagement with the hames the tug is passed through the buckle 75 its perforations being engaged by the stud or tongue of the same, whichever may be employed, and the remaining portion of the tug passed under the keepers 3—9, and 13.

To the rear side of the tug-strap 18 the plate 2 and the plate 5 I rivet at 20 a leather guard 21, which produces a smooth surface 85 adjacent to the horse.

It will be seen that the tug is flexible by reason of the joints produced therein and may conform to the exterior of the horse, being comfortable, and at the same time that the 90 finish of the same is such as to render it ornamental. The device being formed of metal is of course devoid of stitches, and hence great durability results. It will be observed that the tug-strap is adjustable in the buckle and 95 of course the trace thereby lengthened, and I secure an increased adjustability by reason of the adjustable connection between the plate 1 and the plate 10. When these plates are connected the tug-strap lying in the keepers prevents a disconnection, retaining the parts together. By reason of the flexible joint between the front end of the plate 10 and the buckle-plate 15 it will be seen that the tug- 100

strap may be readily inserted under the keepers 13, and on through the remaining keepers, 3-3 and 9.

Having described my invention, what I claim is—

- 5 1. In a hame-tug, the combination of a tug plate having transverse keepers and provided with a series of transverse slots, and the trace and adjusting plates located respectively at 10 the rear and front ends of the tug plate, and provided at their outer ends with transverse keepers, and having at their inner ends hooks detachably engaging slots of the tug plate, substantially as described.
- 15 2. In a hame-tug, the combination with the tug-plate having the opposite side flanges and its bottom provided with a series of transverse slots, the trace-plate slotted at its rear end to engage with the trace and having its 20 front end reduced and bent to form a tongue engaging the rear slot of the tug-plate, of the adjustable-plate arranged in the tug-plate and terminating at its front end in a reduced tongue and at its rear end bent to form a 25 tongue for engaging the slots in the tug-plate keepers formed on the tug, trace and adjustable plates, a buckle-plate bent to engage a buckle and having its rear end slotted to en-

gage the tongue of the adjustable plate, the buckle arranged in the front bent end of the 30 buckle-plate, the tug-strap terminating at its front end in an eye engaged with the buckle and passing under the several keepers of the several plates, the guard at the inner side of the tug and secured to the tug-strap, trace-plate and tug-plate, and the trace engaging the rear end of the trace-plate, substantially as specified.

3. In a hame-tug, the tug-plate 1 having transverse keepers 3, and provided with a series of transverse slots 4 whose edges are rounded or flared, combined with the trace-plate 5 located at the rear end of the tug-plate and engaging with one of the slots thereof and provided with keeper 9 and tongue 8, and an 40 adjusting plate 10 provided with a keeper 13 and tongues 11 and 12, for the purpose set forth.

In testimony that I claim the foregoing as my own I have hereto affixed my signature in 50 the presence of two witnesses.

WILLIAM TIMMINS.
